BARREL REST

George D. Meyer, Cincinnati, Ohio

Application November 2, 1945, Serial No. 626,257

5 Claims. (Cl. 248—146)

1

This invention relates to a rest or support for barrels and drums and is particularly concerned with a pedestal of simple construction which can be readily affixed to the end or ends of a conventional metal barrel for the purpose of elevating the barrel to a height at which a spigot can readily be inserted into the shell of the barrel and the fluid contained therein drawn off.

In dispensing fluids such as motor oil, anti-freeze compounds, varnish, thinners and the like it is frequently desirable to utilize the original shipping container which in the case of most of the products mentioned is a corrugated steel barrel or drum of conventional construction. If a barrel of this type is elevated from the ground and a spigot is inserted in the head it is possible to draw off the liquid more quickly, more conveniently and in many operations more cheaply than in any other way. In addition, under many circumstances such as in bulk oil plants the original container is conventionally refilled after the liquid has been exhausted and performs a continuing dispensing function.

There have been various types of rests and stands suggested for these purposes in the past but none have met with any pronounced degree of commercial success due to the fact that they have been complicated and expensive to construct, difficult to attach and in many instances have not provided the strong and sure support which is requisite in a structure which is designed to support several hundred pounds of dead weight.

One of the objects of the present invention has been to provide a barrel rest or support which is of extreme simplicity in construction, only three principal elements being required for each end unit.

Another object has been to provide a construction which can be secured directly to the barrel or drum with such a degree of rigidity that in effect it becomes almost an integral part of the barrel itself.

Another object has been to provide a structure which absolutely prevents all rotation of the barrel when in supported position.

Another object has been to provide a construction in which the component elements may be readily disassembled and packed in a compact easy-to-handle unitary package.

Another object has been to provide a construction which in the case of an empty barrel can be readily attached by a single person without the utilization of tools and which in a modified form can be attached to and utilized with a filled barrel with almost equal facility.

2

Other and further objects and advantages will be apparent from the further and more detailed description of a preferred embodiment of the invention when considered in conjunction with the drawings in which:

Figure 1 is an end view of the device of the invention in position on the end of a metal barrel of conventional construction and in which a spigot has been inserted.

10 Figure 2 is a side view of the same construction illustrating two units secured to the barrel and joined together by a draw rod, the use of which is largely optional as will be hereinafter explained.

Figure 3 is a sectional view along the line 3—3, Figure 2.

Figure 4 is a sectional view along the line 4—4, Figure 3.

Figure 5 is a sectional view along the line 5—5, Figure 3.

20 Considering Figures 1 and 2, the preferred embodiment of the invention is constituted by the assembly of three elements which comprise a single support, which assembly has been designated generally as 10. The elements include a collar 11, preferably of arcuate configuration, and a pair of legs 12—12 which are adapted to be inserted through openings in the lower surface of the collar to engage the outer shell of the barrel 13 and thereby to provide a rest or support which will suspend the barrel and the spigot 14 in a dispensing position.

As shown in Figure 2, the preferred use of the invention contemplates a support of identical construction at each end of the barrel. Optionally, these two supports may be joined by a draw rod 15 which has its ends inserted through projecting ears 16 on the under side of the collar and secured by nuts 17 affixed to the screw-threaded ends 26 of rod 15. This draw rod 15 is not essential to the utility of the invention but it does perform a useful function, particularly in the case of a barrel which is filled with liquid at the time the pedestals are secured thereto. In addition, it has a certain general utility in providing a degree of protection against endwise spreading of the legs which may be desirable under certain particular circumstances.

The mode of attachment of the device to a barrel can be best appreciated by a consideration of Figure 4. As illustrated in this figure it will be noted that the conventional steel barrel 13 with which the device is intended to function includes a peripheral flange 18 which projects outwardly from the head 19 of the barrel. At its outermost extremity this flange has a bead 20 extending

laterally from the flange and peripherally around the edge thereof. In affixing the device in attaching position the flange 18 is inserted in a groove 21, preferably of arcuate configuration, formed in the inner surface of the collar 11. This groove may extend the entire width of the collar and may curve on a radius approximating that of the flange 18. Thereupon the legs 12 are inserted through the bores 23 in the lower surface of the collar. Preferably, these openings are 10 screw threaded as are also the ends of the legs as at 22. Each leg is screwed upwardly through its corresponding bore until its extended end 24 engages the shell of the barrel 25 behind the bead 20. In this position the upper surface of the 15 groove 21 in the collar will rest on the inner surface of the flange 18 and the upward movement of the legs against the outer surface of the flange and the barrel shell exerts a clamping action which secures the pedestal tightly to the barrel. Assuming that the screw threads on the leg ends and their corresponding bores are clean and lubricated, a very tight positioning can be accomplished by merely screwing the legs by hand. However, if desired, the legs may have lateral bores through which a spike may be inserted for 20 twisting, or a wrench may be employed.

After the first rest has been positioned, the second one is secured in a similar way and these two rests alone will effectively support the conventional barrel. In the case of an empty barrel the rests can be affixed while it is standing on its end or on its side with equal facility. Where the barrel is filled it will ordinarily require more than one person to place it upright after the rests have been affixed. However, where more than one person is not available it is quite practical to affix one rest to the upper end of a barrel standing on its end and the collar portion only of the second rest to the under end of the barrel. When the two collar portions have been secured and connected by the draw rod 15 the barrel can then be lowered on the one pair of legs and utilized for dispensing while in an inclined position. With the draw rod secured to the collar which has been placed on the lower end of the barrel any tendency of the legs to spread forward due to the uneven distribution of the weight of the barrel is avoided. Thereafter as the fluid is dispensed from the barrel and the weight becomes lighter the second pair of legs may be inserted to provide a structure as shown in Figure 2.

It should be noted that although the collar is secured to a flange only of the barrel the legs are positioned at least partially beneath the barrel itself thereby absorbing the direct weight of the load.

One particular advantage of the structure which should be emphasized is that rotation of the barrel is absolutely prevented. This was a common defect in other types of structures adapted for this purpose and one which rendered these structures more or less impractical. In the preferred construction of the present invention the legs can readily be secured to the barrel with such rigidity that any possibility of rotation is completely avoided.

The component elements of the device are simple to manufacture from materials which are readily available. The collar 11 is preferably cast from iron or aluminum. The legs may be ordinary pipe and the draw rod 15 may also be pipe of a slightly smaller diameter. The elements of each unit are so configurated that they may be

conveniently packed in an assembled package for sale over the counter.

It will be appreciated that the construction herein shown and described constitutes the preferred embodiment of the invention but that various changes of form may be made without departing from the principles of construction as herein described and as set out in the ensuing claims.

Having described my invention, I claim:

1. A support for a barrel having a peripheral flange extending outwardly from an end thereof, comprising a collar member having opposing surfaces, one of said surfaces being adapted to seat on the inner surface of the barrel flange, said collar member having bores therein extending perpendicular to the side of the barrel and being screw threaded, legs inserted into said bores and extending radially from the barrel to provide supports therefor, the upper ends of said legs being screw threaded whereby a clamping contact may be provided between the upper ends of the legs and the side of the barrel.

2. A rest for supporting a barrel, comprising a collar having a groove on the inner face thereof for engagement with the outstanding peripheral flange of a barrel head and having spaced bores therein extending perpendicular to the side of the barrel and legs inserted in said bores for engaging the side of the barrel.

3. A support for a barrel having a peripheral flange outstanding from an end thereof and a peripheral bead disposed outwardly from said flange for maintaining said barrel in sidewise position with respect to the ground, said support comprising two units of identical construction, each unit being secured to a respective end of the barrel, each unit comprising a collar having an arcuate groove on the inner face thereof for engagement with the flange of the barrel and a pair of legs inserted through the collar in a screw threaded connection and extending radially therefrom and engaging the side of the barrel inwardly of the bead, and brace means extending lengthwise of the barrel and attached to the two units for preventing endwise collapsing thereof.

4. A support for a barrel having a circumferential peripheral flange outstanding from an end thereof, said support comprising an elongated plate having an arcuate groove formed in the inner face thereof for engagement with an arcuate portion of the barrel flange and a pair of legs extended radially from the plate; said legs being inserted into the plate from the under side thereof.

5. A support for a barrel having a circumferential peripheral flange outstanding from an end thereof, said support comprising an elongated plate having an arcuate groove formed in the inner face thereof for engagement with an arcuate portion of the barrel flange, a pair of legs extending radially from the underside of the plate, and means for securing the support at the barrel flange.
